(Cl. D54—6)

FIG. 1

FIG. 2

FIG. 4

FIG. 6

FIG. 7

FIG. 3

FIG. 5

FIG. 1 is a top plan view showing my new design for a tool holder;

FIG. 2 is a side elevational view;

FIG. 3 is a bottom plan view;

FIG. 4 is an end elevational view taken from the right-hand side of FIG. 2;

FIG. 5 is a longitudinal sectional elevational view taken along line 5—5 of FIG. 1;

FIG. 6 is a sectional plan view taken along line 6—6 of FIG. 2; and

FIG. 7 is a transverse sectional elevational view taken along line 7—7 of FIG. 2.

An end elevational view taken from the lefthand side of FIG. 2 would be the same as that shown in FIG. 4.

I claim:

The ornamental design for a tool holder, substantially as shown and described.
